BOOT WITH WELTED SOLE CONSTRUCTION

Paul D. Earl, Malone, N. Y., assignor, by mesne assignments, to The Cambridge Rubber Company, a corporation of Maryland

Application February 6, 1947, Serial No. 726,778

1 Claim. (Cl. 36—14)

1

This invention relates to boots and shoes for wear in extremely cold weather wherein a certain degree of insulation of the foot from external low temperature air is incorporated, and it consists in the constructions, arrangements and combinations herein described and claimed.

It is a particular object of the invention to provide an improved sole and welt construction over that disclosed in my prior Patent No. 2,394,433, thereby insuring the production of a boot or shoe which will be more waterproof.

More specifically, it is an object of the invention to provide a unitary sole and welt which may be readily cemented to the insole and lower portion of the upper of a boot, to effectively 15 waterproof the same.

Additional objects, advantages and features of invention will be apparent from the following description considered in conjunction with the accompanying drawings, wherein

Figure 1 is a perspective view of a boot constructed in accordance with the invention, with the toe portion cut off in a plane at right angles to the longitudinal axis of the shoe so as to show the shoe in cross section.

Figure 2 is an enlarged cross sectional view of the shoe adjacent the ball of the foot thereof, before application of the outer sole and welt.

Figure 3 is a similar view of the completed boot.

Figure 4 is a cross section illustrating the manner of securing the lining and insole of the boot.

Referring more particularly to the drawings and procedure in production of the shoe, a lining 15 is first stitched into the shoe vamp and stitched to the quarter and the upper 10 of the shoe as indicated at 10'. The vamp 11 and quarter 12 are joined together conventionally, with a taped seam 13 at the junction of the upper and quarter. The forward portion of the vamp is preferably formed integrally with the quarter 12 at respective sides thereof but is divided longitudinally over the toe portion. The lining 15 is attached to the vamp and quarter and similarly divided in the vamp and toe of the shoe. The division between the vamp and lining is preferably left open until after the mid sole 19 has been attached, after assembly of the lining pieces 15 along the vamp, toe and quarter.

After assembly of the upper as indicated, a lining 15' is positioned over the foot and heel portions of the assembly and is stitched to the upper. As shown, the linings 15 and 15' are formed of fleece sheepskin, suitably sheared, with

2

the fibers presented toward the inside of the shoe. In the attachment of the insole 17 together with the vamp 11 and quarter 12 and lining 15, the latter having been already attached 5 at the seam 13 and along the seam 16, if desired, or this attachment omitted until after attachment of the insole. The parts are laid together as shown in Figure 4, the edges of the lining 15, 15' and vamp 11 being alined, with the edges of the insole 17 and then stitched as at 18. This completes the lining with the vamp and quarter attached. The middle seam 16 of the vamp may be tacked temporarily. The assembly is then placed on a last and the exposed under side of the insole 17 is now coated with a suitable adhesive, and a thick midsole 19 of felt or other good insulating material of a flexible nature and of suitable thickness, previously coated with stiff cement is applied, as shown in Figure 2, and it 10 may be put under suitable pressure to effect a good union. Thereafter, and while the shoe is still lasted, additional adhesive is applied to the under face of the mid-sole 19 as well as upon the lower portion of the quarter 12, the adhesive being extended a substantial distance above the line of stitching 18. A crepe rubber welt 20 of a length so as to extend circumferentially around the mid-sole 19, with the ends overlapped as at 20', is applied to the adhesive surface of the upper, the welt being of a width so as to overlie 15 the mid-sole when turned inwardly thereupon, the adhesive on the mid-sole securing the welt thereto. Adhesive is applied to the exposed side of the inturned portion of the welt and also to the mid-sole 19, if necessary, and an out-sole 21 20 of crepe rubber is then applied and cemented to the mid-sole.

The mid-sole 19 may be of uniform thickness throughout, extending from the heel portion of the shoe to the toe tip, and the out-sole 21 may likewise be of uniform thickness from heel to toe, although other practices may be carried out in accordance with conventional methods. After emplacement of the out-sole as shown and described, the tacking at seam 16 may be removed 25 and the shoe unlasted. Thereafter, the seam 16 may be permanently closed, and a tape 22 applied thereover, as an effective closure. The front and upper may be laced or otherwise closed, as desired.

It will be seen that with the out-sole securely cemented to the mid-sole and the inturned portion of the welt, with the latter having a substantial portion cemented to the upper above the line of securement between the insole linings

and quarter of the shoe, the boot will be effectively waterproofed.

I have disclosed my invention with particularity in the best form known to me, but it will, nevertheless, be understood that this is exemplary, and that modifications in the construction, arrangement and combinations of parts, substitution of materials, structural and otherwise, may be made without departing from the spirit of the invention, within the scope of the appended 10 claim.

I claim:

A footwear of the character described comprising a fleeced lining therewithin, the edges of the lining and upper being flush, an insole being arranged transversely of the lower edges of the upper and lining and being flush therewith and secured thereto, a mid-sole of heat insulating material adhesively secured upon the outer surface of said insole, a crepe rubber welt adhesively secured to the upper at a point a substantial distance above the line of securement between the upper, lining and insole, said welt having a sub-

stantial width and inturned upon the mid-sole and adhesively secured thereto, the terminal ends of said welt being arranged in overlapped relation along a side of the insole and inwardly thereof, and an out-sole of crepe rubber being adhesively secured to said mid-sole and inturned portion of the welt.

PAUL D. EARL.
